US00D948163S

(12) **United States Design Patent** (10) **Patent No.:** **US D948,163 S**
Kreamer (45) **Date of Patent:** **** Apr. 12, 2022**

(54) **PET TREAT**

(71) Applicant: **Spectrum Brands, Inc.**, Middleton, WI (US)

(72) Inventor: **Marc Kreamer**, Delray Beach, FL (US)

(73) Assignee: **Spectrum Brands, Inc.**, Middleton, WI (US)

(**) Term: **15 Years**

(21) Appl. No.: **29/820,604**

(22) Filed: **Dec. 22, 2021**

Related U.S. Application Data

(60) Continuation of application No. 29/667,442, filed on Oct. 22, 2018, now Pat. No. Des. 942,117, which is a (Continued)

(57) **CLAIM**

The ornamental design for a pet treat, as shown and described.

DESCRIPTION

FIG. 1 is a front, top, and left perspective view of a first embodiment according to the new design;

FIG. 2 is a left side elevation view thereof;

FIG. 3 is a right side elevation view thereof;

FIG. 4 is a front elevation view thereof;

FIG. 5 is a rear side elevation view thereof;

FIG. 6 is a top plan view thereof;

FIG. 7 is a bottom plan view thereof;

FIG. 8 is a front, top, and left perspective view of a second embodiment according to the new design;

FIG. 9 is a left side elevation view thereof;

FIG. 10 is a right side elevation view thereof;

FIG. 11 is a front elevation view thereof;

FIG. 12 is a rear side elevation view thereof;

FIG. 13 is a top plan view thereof; and,

FIG. 14 is a bottom plan view thereof.

The broken lines shown FIGS. 1–14 illustrate portions of the pet treat that form no part of the claimed design.

1 Claim, 8 Drawing Sheets

Related U.S. Application Data

continuation of application No. 29/589,594, filed on Jan. 3, 2017, now Pat. No. Des. 831,297, which is a division of application No. 29/549,670, filed on Dec. 28, 2015, now Pat. No. Des. 781,525.
